[57] CLAIM

The ornamental design for a combined grill and oven, as shown.

DESCRIPTION

FIG. 1 is a front elevational view of a combined grill and oven showing our new design;

FIG. 2 is a left side perspective view thereof;

FIG. 3 is a right side perspective view thereof;

FIG. 4 is a top plan view thereof; and,

FIG. 5 is a right side elevational view thereof.

The undisclosed bottom view is plain and unornamented.
